UNITED STATES PATENT OFFICE.

EDGAR C. WILEY, OF LYNCHBURG, VIRGINIA, ASSIGNOR OF ONE-HALF TO
HENRY E. MCWANE, OF SAME PLACE.

FIRE-PLUG.

SPECIFICATION forming part of Letters Patent No. 595,506, dated December 14, 1897.

Application filed April 26, 1897. Serial No. 633,950. (No model.)

To all whom it may concern:

Be it known that I, EDGAR C. WILEY, a citizen of the United States, residing at Lynchburg, in the county of Campbell and State of Virginia, have invented a new and useful Improvement in Fire-Plugs, of which the following is a full, clear, and exact description.

My invention is an improvement in fire-plugs or hydrants; and it consists in certain novel constructions and combinations of parts, as will be hereinafter described, and pointed out in the claim.

In the drawings, Figure 1 is a vertical longitudinal section of my hydrant. Fig. 2 is a side view of the upper part thereof. Fig. 3 is a detail section of the plug-valve seat. Fig. 4 is a top plan view of said seat, and Fig. 5 is an enlarged section of the lower end of the plug. Fig. 6 is an enlarged section on line 20 6 6 of Fig. 1.

The plug is shown as consisting of the casing A and the stand-pipe B, the latter fitting within the casing and clamping the plug-valve seat C in place. In connecting the stand-pipe 25 and casing to secure this clamping of the valve-seat C, I provide the casing internally near its upper end with seats for the bolts D, which connect the stand-pipe and casing, and provide for these bolts openings in the stand-30 pipe in line with the interior of the casing, as best shown in Fig. 1, in order to secure the clamping together of the casing and stand-pipe without any lateral projections to afford a surface against which the earth may press 35 as it swells in such manner as to lift the plug. I also seek to form the plug in such shape as to avoid any lifting thereof by the upswelling of the ground by tapering the casing A inward slightly from a point slightly below its middle. 40 to its upper end, such taper being in practice very slight and hardly perceptible to the eye.

In the specific construction shown of the connection between the casing and stand-pipe I form the casing near its upper end with the 45 internal upper and lower flanges E and F, spaced apart and affording between them a seat for the heads d of the bolts D. The flange E is provided at intervals with slots e, which permit the passage of the heads d of 50 the bolts, which when inserted may be slipped beneath the flange E by a partial turning of

the stand-pipe B, and the said bolts may be removed by reversing such operation, thus enabling the application and removal of the stand-pipe without entirely removing the nuts 55 of any of the bolts D.

The stand-pipe B is provided on its outer side with a ring-like projection G, which has formed through it the openings g for the bolts D, thus forming a strong connection for such 60 bolts D in such manner as to avoid any lateral projection beyond the side of the casing A.

The valve H, being the plug-valve, is fitted to the seat C and is preferably double-faced, 65 having its packing formed with the two faces h h, so it may be reversed when worn or when one face for any other reason is defective.

The casing A is provided with the waste-outlet, and a suitable vent-outlet is provided 70 leading from the stand-pipe into the casing. This vent-outlet is shown as formed through the valve-seat C, controlled by a valve I, operating on a seat J, which controls the openings j, which lead from the interior of the 75 stand-pipe and are formed in a tubular extension J', which surrounds and projects upwardly from the seat J for the valve I. This valve I is weighted at I' and is provided at I' with a portion which projects into position 80 for engagement by the valve H when such valve is closed, so the closing of the valve H will open the valve I to permit water within the stand-pipe to pass out through the opening j and valve-seat J into the casing and 85 thence out the opening j, as will be understood from Figs. 1 and 5.

As best shown in Figs. 3 and 4, the vent-outlet is formed integral with the valve-seat C, and in order to receive the tubular extension J' and the valve I, I provide the stand-pipe B with a lateral pocket B', as shown in Figs. 1 and 5, such pocket furnishing on the stand-pipe an offset corresponding to the offset formed at C' on the valve-seat C, which 95 results from the provision of parts J J', as best shown in Fig. 4. This arrangement of the vent-outlet is certain in its operation, permits the draining of the stand-pipe down to a point but a short distance above the plug-valve, 100 and furnishes both the plug-valve seat and the vent-outlet-valve seat in the same part,

facilitating both the manufacture and application thereof, as will be understood from the drawings.

Having thus described my invention, what 5 I claim, and desire by Letters Patent, is—

A plug comprising the casing having internally near its upper end upper and lower flanges forming a seat for the bolt, the upper flange being slotted for the passage of the

bolt-heads, the stand-pipe having on its outer 10 side a ring-like projection provided with openings for the bolts, and the bolts passed through said openings and fitted to engage with the seat of the casing, substantially as described.

EDGAR C. WILEY.
